UNITED STATES PATENT OFFICE.

WILLIAM I. LEITCH, OF CLEVELAND, OHIO.

ADJUSTABLE COLLAPSIBLE BIER AND TOP THEREFOR.

Application filed June 27, 1921. Serial No. 480,545.

To all whom it may concern:

Be it known that I, WILLIAM I. LEITCH, a citizen of the United States, and a resident of Cleveland, county of Cuyahoga, and State 5 of Ohio, have invented a new and useful Improvement in Adjustable Collapsible Biers and Tops Therefor, of which the following is a specification, the principle of the invention being herein explained and the best mode in 10 which I have contemplated applying that principle, so as to distinguish it from other inventions.

The present invention relates to a collapsible and adjustable bier and a top for the 15 same which is also collapsible, so that the bier and top may be folded into compact units and thus handled and carried about easily. One of the objects is the provision of a bier which may be adjusted for various 20 sized coffins and which will be with its top, suitable for the usual standard sizes of coffins now in use. To the accomplishment of the foregoing and related ends, said invention, then, consists of the means hereinafter 25 fully described and particularly pointed out in the claims.

The annexed drawing and the following description set forth in detail certain mechanism embodying the invention, such 30 closed means constituting, however, but one of various mechanical forms in which the principle of the invention may be used.

In said annexed drawing:—

Fig. 1 is a front elevational view of the 35 bier and the top in place; Fig. 2 is a side elevational view of the same; Fig. 3 is a sectional view through the collapsible top showing the position of certain of the parts when collapsed in dotted lines; Fig. 4 is a rear 40 elevational view of the top in its collapsed position on the line 4—4 of Fig. 3; Fig. 5 is a front elevational view of the bier in its extended condition showing the use of the center insert; Fig. 6 is a sectional view on the line 6—6 of Fig. 5; Fig. 7 is a sectional view on the line 7—7 of Fig. 6; Figs. 8 and 45 9 are elevational views of the two pieces shown in Fig. 7; Fig. 10 is a rear elevational view of the frame and removable panel; Fig. 11 is a sectional view on the line 11—11 50 of Fig. 10; and Fig. 12 is a sectional view on the line 12—12 of Fig. 5 showing the removable sleeves for the molding.

The present bier is shown as being made so that it may be used with the three ordinary sizes of coffins which are full size, junior size, and baby size. In Fig. 5 the bier is shown as being ready to receive a full size coffin while the bier proper shown in Fig. 1 will take a junior size coffin and when the collapsible top is used, the bier will receive a baby size coffin. As best shown in Figs. 1, 2, and 5, the bier consists of three sections, 1, 2 and 3, the two outer sections 1 and 3, being provided with hinged ends 4 so that the 65 outer front sections and the ends may be folded flat together in order to pack and carry the bier. These sections are adapted to be removably attached together and in Fig. 5 the front sections are shown as having their meeting faces 5 provided with interlocking members so that they can be attached together securely when the bier is set up. As best shown in Figs. 6, 7, 8 and 9, the meeting surface of the end member 1 is 70 provided with a plate 6 having two or more lugs 7 formed thereon which lugs are adapted to be received in bayonet slots 8 formed in a second plate 9 mounted in a recess 10 in the end 11 of the intermediate section 2. As 75 shown in Figs. 8 and 9, any two adjacent sections may adjust themselves to variations in floor level as the pins 7 can move slightly in the slots 8 without disengagement and thus the ordinary inequalities in floor level will be compensated for as the sections will 80 automatically adjust themselves to the floor level, due to this possible vertical movement of the pins 7 in the slots 8. The right hand end of the intermediate section 2 as shown in Fig. 5, is also provided with a lugged plate 6 while the surface of the end section 3 at the right of Fig. 5 has a slotted plate 9 so that the bier may be put together leaving 85 out the center section as shown in Fig. 1.

The sections of this bier are formed with a bottom molding 15 which is provided with a square frame 16 having a second molding on top 17. Removable panels 18 are mounted in these frame members, the frames being 100 rabbed as at 19 to receive the panels and key slots or recesses 20 are formed in the frames to receive the eccentrically mounted locks 21 carried on the backs of the panels. The moldings are adapted to be covered by 105 removable sleeves 22 which fit over the mold-

ings themselves and are made the proper length to cover the molding of one section. These removable sleeves 22 and the removable panels 18 will be covered with suitable material so that the bier may substantially conform to the appearance of the casket. Where a wooden, cloth covered casket is employed, similar cloth covered sleeves and panels will be used. If a metal casket is employed the sleeves and the panels will be made of the same metal as the casket and thus the appearance of the casket and the bier can readily be made to conform to each other. It is understood of course that the bier as shown, is open at the back and the casket merely rests upon the upper surfaces of the front and end sections. Of course extra sections to close the back may be employed as the sections fit together by means of the lugs and bayonet slots, it is possible to slightly vary the relative position of the sections to compensate for uneven floor conditions and thus the bier when set up, is not only secure but can be made to furnish an even top surface for the casket.

The collapsible top 25 which is used with the bier for small caskets has a rigid upwardly inclined front member 26 to which are hinged the end pieces 27 which are similarly inclined upwardly and inwardly and this front member 26 is provided with a narrow, horizontal top rail 28 to which is hinged the remainder 29 of the top which in its normal position, rests upon the upper surfaces of the end members but which may be folded downwardly into the position shown in dotted lines in Fig. 3 when the top is collapsed. To collapse the top, the end members 27 are swung inwardly against the front member as best shown in Fig. 4 and then hinged top portion 29 is folded down over the end members until the top is collapsed as shown in Fig. 4 and in dotted lines in Fig. 3. It may then be placed in a suitable carrying case so that it may be readily handled. The end members of the top are provided with pins 30 which fit within suitable complementary holes in the end members of the bier so that when the top is placed in position on the bier it is secured thereto against accidental removal.

The top and the bier are thus not only collapsible but together form an adjustable bier which may be used with caskets of practically any size and the bier and top when collapsed may be easily and readily handled and carried about. By the use of the removable sleeves and panels, a single bier with a set of sleeves and panels, may be made to conform to practically all of the styles of caskets and as the user of the bier knows the type of casket which is to be used with the bier at any particular time, it is merely necessary to change the panels and carry along the extra sleeves which fit

the moldings and may thus be carried in place with the sections of the bier.

The present bier construction is such that the bier, when erected, forms a box which is closed at the front and at the ends and merely opens at the back, the front and ends being in substantial alignment with the front face and the ends of the casket, so as to close the air space under the casket from view and thus break up the lines of the casket proper. In this manner the space under the casket is closed instead of being substantially open as is the case where pedestals or stools are used, on which the casket is mounted.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a collapsible bier, the combination of outer front sections having ends hinged thereto, a removable center front section adapted to fit between said outer sections, and interlocking members on the ends of said outer sections and said removable section, whereby said sections may be locked together to form a bier which is closed across the front of the casket.

2. In a collapsible bier, the combination of outer sections having ends hinged thereto, a removable center section adapted to fit between said outer sections, and adjustable interlocking members on the ends of said outer sections and said center section whereby said sections may be secured together and adjusted as to height.

3. In a collapsible bier and top, the combination of a bier comprising front sections adapted to be removably connected together and each section having an end hinged thereto and adapted to be folded flat against the front section, and a collapsible top adapted to be removably mounted on said bier, said top having hinged ends and a hinged top portion adapted to be folded into a substantially flat package to allow said bier and top to be packed together in a flat case when collapsed.

4. In a collapsible bier and top, the combination of a bier comprising front sections having ends hinged thereto, and a collapsible top adapted to rest on said bier and comprising a front member, having two ends hinged thereto, and a top member hingedly attached to said front member.

5. In a collapsible top for a bier, the combination of a front member, two ends hinged to said front member, a top rail attached to said front member, and a top portion hinged to said rail and adapted to be pulled down

over said end pieces when said top is collapsed to form a substantially flat folded device.

6. In a collapsible top for a bier, the combination of a front member, two ends hinged to said front member, and adapted to be folded against the rear of said front member, a top rail attached to said front member, and a top portion hinged to said rail and adapted to be folded down over said ends when said top is collapsed to form a substantially flat folded device.

7. In a collapsible bier for caskets, the

combination of two outer front sections each having an end hinged thereto, and adapted to be swung outwardly at right angles to the section, said sections having interlocking means on the meeting inner ends, said sections also being adapted to be erected into a box closed at the front and ends under and substantially in alignment with the front and end edges of the casket to close the air space under the same from view.

Signed by me, this 23rd day of June, 1921.

WILLIAM I. LEITCH.
